His Attorney.

UNITED STATES PATENT OFFICE.

ASA F. BATCHELDER, OF SCHENECTADY, NEW YORK, ASSIGNOR TO GENERAL ELECTRIC COMPANY, A CORPORATION OF NEW YORK.

LOCOMOTIVE OR CAR TRUCK.

Application filed September 26, 1923. Serial No. 664,970.

To all whom it may concern:

Be it known that I, ASA F. BATCHELDER, a citizen of the United States, residing at Schenectady, in the county of Schenectady,

5 State of New York, have invented certain new and useful Improvements in Locomotive or Car Trucks, of which the following is a specification.

10 My invention relates to locomotive or car trucks and particularly to trucks for electrically propelled locomotives or cars and has for its object to provide a novel and improved mounting for the motors of such trucks which will reduce the dead load on 15 the axles. In locomotives and car trucks it is customary to mount one side of the motors directly upon the axles and resiliently support the other side of the motor from a transom or truck frame. This reduces to 20 some extent the dead weight caused by the motor on the transom or truck frame but leaves a portion of the weight of the motor as dead weight on the axles.

25 My invention consists in providing improved resilient means between the axles and the motors to reduce to a minimum the dead weight upon the axles. My invention further consists in using the electric motors as a part of the mechanical portion of the 30 truck, supporting them between the axles and transom, the transom being supported by equalizers which in turn are supported by the motor frames so that the whole truck structure including the motors is carried by 35 the resilient means interposed between the motors and the axles. In such a truck, the supports of the motors on the axles are used as the main journals, so that no outside journal boxes or any frame are required and at 40 the same time by reason of my improvement the dead weight upon the axles will be reduced to a minimum.

45 Other features of novelty which characterize my invention will be pointed out with particularity in the claims annexed to and forming a part of this specification. For a better understanding of my invention reference may be had to the following description taken in connection with the accompanying drawings in which Fig. 1 is a side elevation of a truck embodying my invention; Fig. 2 is a plan view of the truck shown in Fig. 1; Fig. 3 is an end elevation, partly in section, of a truck embodying my

invention; and Fig. 4 is a view taken along 55 line 4—4 of Fig. 3 looking in the direction of the arrows.

Referring to the drawings, the axles 5 are provided with the usual wheels 6 and are arranged to be driven by electric motors 7. 60 The axles have journal boxes 18 on which the motors 7 are resiliently supported by means of springs 21 to insure a minimum of dead weight upon the axles. I also provide supports on the motors 7 for equalizers 11 and 65 support the transom 8 on springs 24 which are carried by the equalizers 11. The equalizers 11 are secured to the motors 7 by means of pins 12 which pass through the equalizers 11 and lugs 13 formed on the 70 motor frame. These equalizers by reason of this pin connection maintain the proper distance between the axles as will be pointed out hereinafter. Each of the motors 7 is geared to its respective axle through gears 75 14 and 15. The motors 7 have a nose 16 somewhat similar to the ordinary nose on a railway motor, only larger, which fits into a recess 17 in the transom 8 so as to prevent up and down or sidewise movement of the 80 motor 7 with respect to the transom. Part of the weight of each motor is thus carried by the transom 8. The balance of the weight of the motor is carried by the axle 5. Mounted upon the axles 5 are the journal boxes 18 85 having bearings 19. Projecting from the frame of motor 7 are overhanging jaws 20 which engage the journal box 18 to secure the motor to the axle 5. Interposed between the journal box 18 and the motor frame are 90 a plurality of sets of leaf springs 21 aligned with each other and with the axle 5 and having their ends supported in pockets on the top of the journal box 18 and supporting part of the weight of the motor 7 at their 95 centers. This arrangement by reason of the resiliency of the leaf springs 21 will reduce to a considerable extent the dead load upon the axles 5. To lubricate the bearing 19 and the springs 21, I provide an oil well 22 above the journal boxes 18 having outlets 23 which discharge oil over the springs 21 and into the journal box 18. I thereby secure proper lubrication of the springs 21 and the bearings 19 from a common source. The proper 100 distance between the axles is maintained by the two longitudinal bars 11 which act as equalizers and the jaws 20 formed on the

105

motor frame which engage the journal boxes 18. This construction prevents longitudinal movement between the equalizers 11 and the motors 7 and between the motors and the axles 5. By this construction it is possible to dispense with the framework such as it has been customary to employ in the past, to secure proper spacing of the axles. The transom 8 is supported on coiled springs 24 which are carried by plates 25 secured to the ends of tie rods 26. The tie rods 26 are suspended from the equalizers 11 by means of plates 27 which straddle the equalizers. The outer ends of the transom 8 form a support for the brake rigging and air cylinders 28, the brake levers 29 being pivotally connected to the ends of the transom and in line with the wheels 6. The transom has a cavity extending from the center plate opening 30 to outlets 31 formed in the side of the transom. These outlets 31 are provided with sliding sleeves 32 which are biased in an extended position and engage the frame of the motors 7. The motors 7 have openings or air inlets adjacent the sliding sleeves 32 to permit air to be forced into the motors through the center plate opening 30 and the transom 8 for the purpose of cooling them. The sliding sleeves 32 have a finished surface which engages a similar finished surface surrounding the air inlet of the motors 7 and this in conjunction with the biasing means provides a tight joint between the transom and the motor frame for the circulation of the cooling air and at the same time permits relative displacement of the openings.

From the above it will be seen that all the weight on the center plate together with the weight of the equalizers, the transom and the motors, will be resiliently supported by the springs 21 which are interposed between the motors 7 and the journal boxes 18 and that the weight of the transom and the weight carried thereon will be resiliently supported on the equalizers by the coiled springs 24. Such a truck will be light in weight and inexpensive to build, as it does not require any outside journal boxes or outside frame and at the same time by reason of my improvement the dead weight upon the axles will be reduced to a minimum.

I desire to have it understood that my invention is not limited to the particular arrangement shown and described, and I aim in the appended claims to cover all modifications that do not depart from the spirit and scope of my invention.

What I claim as new and desire to secure by Letters Patent of the United States, is:—

1. An axle mounting for railway motors comprising a motor, an axle, wheels on said axle, a journal box on said axle, and a plurality of sets of leaf springs interposed between said motor and said journal box for

supporting said motor, said sets of springs being aligned with each other and with said axle.

2. An axle mounting for railway motors comprising a motor, an axle, wheels on said axle, a journal box on said axle between said wheels, jaws formed on said motor engaging said journal box, and resilient means interposed between said journal box and said motor for supporting said motor comprising a plurality of sets of leaf springs having their ends supported on said journal box and supporting said motor at their centers, said sets of springs being aligned with each other and with said axle. 80

3. An axle mounting for railway motors comprising a motor, an axle, wheels on said axle, a journal box on said axle, a bearing in said journal box, spring means interposed between said journal box and said motor, and means whereby said spring means and said bearing are lubricated from a common source. 85

4. An axle mounting for railway motors comprising a motor, an axle, wheels on said axle, a journal box on said axle, and resilient means interposed between said motor and said journal box for supporting said motor comprising a plurality of sets of leaf springs having their ends supported on said journal box and supporting said motor at their centers, said sets of springs being aligned with each other and with said axle. 90

5. A locomotive or car truck comprising wheels, axles therefor, a truck transom, electric motors geared to said axles, said axles having journal boxes mounted thereon, equalizers supported by said motors, said transom being supported on said equalizers, and resilient means interposed between said journal boxes and said motors whereby the dead weight upon the axles is reduced to a minimum. 100

6. A locomotive or car truck comprising wheels, axles therefor, a truck transom, electric motors geared to said axles, said axles having journal boxes mounted thereon, equalizers supported by said motors, said transom being supported on said equalizers, and resilient means interposed between said journal boxes, and said motors comprising leaf springs having their ends supported on said journal boxes and supporting said motors at their center. 110

7. A locomotive or car truck comprising wheels, axles therefor, a transom, electric motors geared to said axles, said axles having journal boxes mounted thereon, equalizers supported by said motors, said transom being supported on said equalizers, resilient means between said journal boxes and said motors, and resilient means for supporting said transom on said equalizers. 115

8. A locomotive or car truck comprising wheels, axles therefor, a truck transom, elec- 130

- tric motors geared to said axles, journal boxes on said axles, jaws on said motors engaging said journal boxes to prevent longitudinal movement between said motors and said axles, equalizers connecting said motors and supported thereby, said transom being supported on said equalizers, and resilient means between said journal boxes and said motors whereby the weight on said axles is resiliently supported.
9. A locomotive or car truck comprising wheels, axles therefor, a truck transom, electric motors geared to said axles, said axles having journal boxes mounted thereon, equalizers, resilient means between said motors and said journal boxes for supporting said motors, each of said motors being supported on said transom, and spring means supporting said transom on said equalizers.
10. A locomotive or car truck comprising wheels, axles therefor, a truck transom, electric motors geared to said axles, journal boxes on said axles, equalizers, supports on said motors for said equalizers, resilient means between said motors and said journal boxes for supporting said motors and said equalizers, each of said motors being also supported on said transom, and resilient means carried by said equalizers for supporting said transom.
11. A locomotive or car truck comprising wheels, axles therefor, a truck transom, electric motors geared to said axles, journal boxes between the wheels of said axles, jaws on said motor frame engaging said journal boxes to prevent longitudinal movement between said motors and said axles, resilient means between said motors and said journal boxes for supporting said motors, equalizers, supports on said motors for said equalizers, and resilient means carried by said equalizers for supporting said transom.
12. A locomotive or car truck comprising wheels, axles therefor, a truck transom, electric motors geared to said axles, journal boxes on said axles, jaws on said motors engaging said journal boxes to prevent longitudinal movement between said motors and said axles, resilient means between said motors and said journal boxes for supporting said motors, equalizers, and resilient means carried by said equalizers for supporting said transom.
13. A locomotive or car truck comprising wheels, axles therefor, a truck transom, electric motors geared to said axles, said axles having journal boxes mounted thereon, jaws formed on said motors engaging said journal boxes, resilient means between said motors and said journal boxes for supporting said motors, said motors being also supported by said transom, longitudinally extending equalizers secured to said motors for spacing said axles, and means carried by said equalizers for resiliently supporting said transom.
14. A locomotive or car truck comprising wheels, axles therefor, a truck transom, electric motors geared to said axles, said axles having journal boxes mounted thereon, each of said motors being also supported by said transom, brake rigging for said wheels carried by said transom, equalizers, supports on said motors for said equalizers, resilient means interposed between said motors and said journal boxes for supporting said motors on said axles, and resilient means interposed between said transom and said equalizers for supporting said transom and motors on said equalizers.

In witness whereof, I have hereunto set my hand this 25th day of September, 1923.

ASA F. BATCHELDER.
